UNITED STATES PATENT OFFICE.

JOHN J. BRINKERHOFF, OF AUBURN, NEW YORK.

BARB FOR FENCES.

SPECIFICATION forming part of Letters Patent No. 269,631, dated December 26, 1882.

Application filed August 23, 1882. (No model.)

To all whom it may concern:

Be it known that I, JOHN J. BRINKERHOFF, a citizen of the United States, residing at Auburn, in the county of Cayuga and State 5 of New York, have invented new and useful Improvements in Barbs for Fences, of which the following is a specification.

My invention relates to sheet-metal barbs for fence-wires, and has for its object the provision of a blank which can be economically cut from a strip or sheet of metal in substantial accordance with the method set forth in a patent heretofore granted J. and W. M. Brinkerhoff, No. 258,014, dated May 16, 1882, and 15 which, when produced by that or any other method, will, by reason of the contour and relative location of the parts of the blank, be capable of ready and firm attachment to a strand or rail; and to this end my invention 20 consists in certain features hereinafter described, and specifically set forth in the claim.

Referring to the drawings, Figures 1, 4, 7, 10, and 13 are plans of barb-blanks constructed in accordance with my invention. Figs. 2, 5, 25 8, 11, and 14 are perspectives, respectively, of the above-mentioned blanks in the form they assume when attached to a strand or rail; and Figs. 3, 6, 9, 12, and 15 are perspectives, respectively, of said blanks and a portion of a 30 rail comprising two strands.

Like letters refer to like parts in all the figures.

The requisites of a practicable barb-blank are economy in its production, readiness of 35 application to the strand, and a natural tendency of the barbs of the blank to assume the proper direction and extent of projection by means of the force applied in setting the blank to the strand. It will be noticed that each of 40 the blanks shown comprises a body portion, A, and a series of barbs arranged to project in opposite directions from said body portion and of different lengths, each directly merged into the body portion and one or more of them 45 separated from its or their companion barbs, or from a lip which performs a certain function of the barbs, as hereinafter described, the separation of the barbs leaving a space opposite the base of one of the series, in order that 50 in their application they may pass by each other and assume the desired form. As illustrated, these features are applicable to barb-

blanks having three or more barbs and to barbs having barbs which merge into a body portion at their barbless bases, and which, when applied, remain in a substantially unbent condition—a feature in itself not herein claimed, as it is shown in another case filed simultaneously herewith.

Specifically the blank comprises the barbs 6c B, C, D, and E, and a lip, a, formed by the outline of the blank and the slits 1 and 2 on either or both in accordance with the particular arrangement of the barbs to bring or locate the spaces x as desired. The function of 65 the lip a is to complete the embracement of a strand by a barb without undue consumption of its length, so that when applied the barbs of a blank will project equal distances, and this function of embracement may be performed in the absence of a lip by increasing 70 the length of a barb in the blank.

If, in a three-barbed blank, as Fig. 1, it is desired to locate the space x between the barb B and lip a, then slit 1 alone is made, while in 75 other locations of the space or spaces slits 1 and 2 are both made, the latter completing the outline or formation of the lip and a portion of an adjacent barb.

In applying the blank to a strand it will be 80 seen that in setting the body A to the strand, so as to conform to its circumference, the barbs and lips naturally take the desired positions or angles of projection by reason of the relative location of barbs and spaces and lip, and 85 such location is susceptible of many variations, exceeding in number those shown, all embodying the gist of my invention. I therefore do not limit myself to any of the specific arrangements illustrated, but deem the features of 90 construction which coact to render the blank readily applied and naturally assuming a desired distance and angle of projection in each barb as of my invention. When applied to a fence-rail of two or more strands, as F G, 95 one or more of the barbs may pass between the strands, if desired.

Having thus described my invention, what I claim is—

A barb-blank for fence-wire, consisting of 100 the body portion A, provided with barbs B, C, and D, which extend in opposite directions, as described, and with a lip, a, opposite one of the barbs, said barbs and lip being separated

by slits and a vacant space, *x*, and the blank thus formed being applied to a fence-wire with the lip bent so as to meet the opposite barb and the several remaining barbs respectively bent around the wire and left in a substantially unbent condition, substantially as shown, and for the purpose specified.

In testimony whereof I have hereunto set my hand in the presence of two subscribing witnesses.

JOHN J. BRINKERHOFF.
